(57) **CLAIM**

I claim the ornamental design for a wickless candle with an electrical switch, as shown and described.

DESCRIPTION

FIG. 1 is a perspective view of a wickless candle with an electrical switch.

FIG. 2 is a front elevational view of a wickless candle with an electrical switch.

FIG. 3 is a top plan view of a wickless candle with an electrical switch.

FIG. 4 is a bottom plan view of a wickless candle with an electrical switch.

FIG. 5 is a side elevational view of a wickless candle with an electrical switch.

FIG. 6 is an opposed side elevational view of a wickless candle with an electrical switch; and,

FIG. 7 is a rear elevational view of a wickless candle with an electrical switch.

In the drawings, the broken dots which appear on the inside of the candle holder depict melted fragrance wax and are part of the claimed design.

1 Claim, 3 Drawing Sheets
